(57) **CLAIM**

The ornamental design for a portable housing for golf swing analyzer, as shown and described.

DESCRIPTION

FIG. 1 is a perspective view of a portable housing for a golf swing analyzer according to the present invention shown in operative position;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a bottom view;

FIG. 8 is a view corresponding to FIG. 1 but showing the portable housing for golf swing analyzer in a closed or carrying position;

FIG. 9 is a front view;

FIG. 10 is a left side view;

FIG. 11 is a rear side view;

FIG. 12 is a right side view;

FIG. 13 is a top view; and,

FIG. 14 is a bottom view.

The broken lines shown in FIGS. 1, 2, 4, and 11 are for illustration purposes only and do not form part of the instant design.
